STETHOSCOPIC INSTRUMENT

James J. Tynan, Milton, Mass.

Application August 4, 1938, Serial No. 222,993

2 Claims. (Cl. 181—24)

This invention relates to improvements in stethoscopic instruments.

It is well known to practicing physicians that several stethoscopes of different forms and sizes are required for auscultative examination of different parts of the human body, as well as grown-up persons and children. Thus, a so-called "bell body piece" with an open sound-collecting space is the most practical for certain examinations, while a so-called "diaphragm body piece" with a diaphragm covered sound-collecting space is more practical for other examinations. Furthermore, the examination of a large area of the human body requires a larger body piece than the examination of apices, interspaces and other body parts of small area for which a small body piece is more practical. Also, some physicians use two different forms of stethoscopes for examining one and the same part of the body as, for instance, in cardiac examinations where a bell body piece registers primarily low-pitched murmurs and a diaphragm body piece registers primarily high-pitched murmurs. In order to be prepared for all contingencies, most physicians have stethoscopes of different forms and of different sizes at their disposal. However, it is the common experience of these physicians that they cannot readily find or reach a particular stethoscope because some stethoscopes of their collection are usually misplaced or at least not within easy reach. Moreover, the acquisitions of several stethoscopes involves considerable cost. Stethoscopes have also made their appearance on the market which come with interchangeable body pieces, but they have not mitigated the frequent confusion and inconvenience experienced by physicians when trying to find or reach for the proper body piece. It is also disturbing to a physician to replace one body piece with another in the middle of an examination.

It is the primary aim and object of the present invention to provide a stethoscopical instrument which comprises body pieces of several forms and sizes that can be readily removed in any number in order to have a particular body piece available for an examination. After the examination is made, all these body pieces that have been removed can be readily reapplied to the instrument in one manipulation.

It is also an object of the present invention to construct the instrument in a manner that all but one of the body pieces thereof conceal their true identity as such and merely appear as a well shaped and conveniently accessible han-

dle portion of the single non-concealed body piece.

Before explaining in detail the present invention it is to be understood that the invention is not limited in its application to the details of construction and arrangement of parts illustrated in the accompanying drawing, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

In the drawing:

Fig. 1 is an enlarged plan view of a stethoscopic instrument which embodies the present invention.

Fig. 2 is a cross-section through the instrument, taken on the line 2—2 of Fig. 1.

Fig. 3 is a section taken on the line 3—3 of Fig. 2.

Fig. 4 is a side elevation of the instrument with all the body pieces thereof in assembled relation.

Fig. 5 is a view of the instrument similar to Fig. 4, with one of the body pieces removed.

Fig. 6 shows the instrument after all but one of the body pieces have been removed.

Fig. 7 illustrates another way in which the present instrument can be used.

Referring to the drawing and more particularly to Figs. 1, 2 and 4, the stethoscopic instrument consists in the present instance of a bell body piece 10 hereafter called "bell piece," and two diaphragm body pieces 12 and 14, hereafter called "diaphragm pieces." The connecting end 16 of any conventional ear tubes (not shown) is applied to a shank 18 of the bell piece 10 and is preferably removably secured thereon by means of the pin and bayonet connection 20, 22 shown in Figs. 1 and 2.

The bell piece 10 has a frusto-conical sound-collecting space or cavity 24 which communicates with the ear tubes through a sound passage 26. Carried by the bell piece 10 and projecting into an enlarged portion 28 of the sound passage 26 thereof is a pin 30 which is adapted to cooperate with a bayonet slot 32 in a shank 34 of the smaller or intermediate diaphragm piece 12 so as to retain the latter on the bell piece 10.

The diaphragm piece 12 is of the cross-sectional shape best illustrated in Fig. 2 and is provided with an annular recess 36 in which is suitably secured, as by cementing, a soft rubber ring 38 on which the bell piece 10 becomes firmly

seated when its pin 30 is locked in the bayonet slot 32. The diaphragm piece 12 is also provided with a concave sound-collecting space or cavity 42 and a sound passage 40 which provides communication between said sound-collecting cavity 42 and the sound passage 26 of the bell piece 10 in the manner illustrated in Fig. 2. The sound passage 40 consists of a through-bore 44 which is disposed coaxially of the sound passage 26 of the bell piece, and a transverse bore 46. Secured to the open end of the sound-collecting cavity 42 of the diaphragm piece 12 by means of a threaded retainer ring 48 is a diaphragm 50 which may be made of any suitable material such as mica. Rotatably mounted in the bore 44 of the diaphragm piece 12 is a sleeve valve 52, having an opening 54 in its annular wall in alignment with the bore 46. Axial removal of the sleeve valve 52 from the bore 44 is prevented by chamfering one end of said bore as at 56 and by providing the adjacent end of the sleeve valve 52 with a crimp 58 which seats against the chamfered end 56 of the bore 44. The sleeve valve 52 is also provided with a knurled disc 60 by means of which it may be rotated. The disc 60 carries a pin 62 which projects into an arcuate groove 64 in the face 66 of the diaphragm piece 12, whereby rotation of the sleeve valve 52 is limited from an angular position in which its opening 54 is completely out of communication with the bore 46 into a position in which said opening is completely in communication with said bore.

The next diaphragm piece 14 comprises a member 70, having an annular rim 72 which passes over the retainer ring 48 of the intermediate diaphragm piece 12 at a sliding fit. The member 70 is also provided with a concave sound-collecting space or cavity 14, to the open end 75 of which is secured a diaphragm 76 by means of an externally knurled and internally threaded retainer ring 78 (see Fig. 2). The member 70 is further provided with a tubular extension 80 which is in communication with the sound-collecting cavity 74 and is threadedly received at 82 in the bore 46 of the intermediate diaphragm piece 12. The tubular extension 80 thereby extends through a central aperture 84 in the diaphragm 50. To reinforce the centrally apertured portion of the diaphragm 50, a preferably metallic ferrule 86 is applied to the diaphragm in the manner shown in Fig. 2. The member 70 of the diaphragm piece 14 is also provided with an annular recess 88 in which is suitably secured as by cementing, a soft rubber ring 90 on which the retainer ring 48 of the intermediate diaphragm piece 12 becomes firmly seated when the other diaphragm piece 14 is applied thereto.

The bell piece 10 as well as the diaphragm 12 and 14 are preferably made of a light metal, such as aluminum, and chromium-plated.

If the physician desires to examine large areas of the human body, he will use the diaphragm piece 14, i. e., he will use the instrument assembled as shown in Fig. 4. If an examination calls for a smaller diaphragm piece, the physician merely removes the larger diaphragm piece 14 by unscrewing the same from the smaller diaphragm piece 12. The physician then uses the assembled instrument shown in Fig. 5. Finally, if an examination calls for a bell piece, the physician will remove the smaller diaphragm piece 12 merely by twisting the same sufficiently to permit withdrawal of the pin 30 from the bayonet slot 32 and then use the instrument in the manner shown in

Fig. 6. If the examination calls immediately for a bell piece, the physician need not remove the larger diaphragm piece 14 from the smaller diaphragm piece 12, but removes both of them from the bell piece 10 in one manipulation, i. e., by merely removing the bell piece 10 from the assembled diaphragm pieces 12 and 14. The replacement of any one of the removed body pieces on the instrument is equally as facile as the described removal therefrom. With the present instrument, a physician has also the choice to use only the two diaphragm pieces 12 and 14 (Fig. 7) on removing the bell body piece 10 therefrom and applying the ear tubes to the shank 34 of the smaller diaphragm piece 12. It is for this reason that the shank 34 is of the same outside diameter as the shank 18 of the bell piece 10 so that the connecting end 16 of one and the same ear tubes may be applied to either shank (Figs. 2 and 7). The bayonet slots 22 and 32 in the bell piece 10 and the smaller diaphragm piece 12 are made identical so that the pin 20 of the connecting end 16 of the ear tubes may also cooperate with the bayonet slot 32 and lock the ear tubes to the smaller diaphragm piece 12 when the instrument is used in the manner shown in Fig. 7. Also, as long as any one of the diaphragm pieces 12 or 14 is used, the volume of the transmitter sound may be regulated by means of the sleeve valve 52.

It appears from Fig. 2 that the various body pieces of the instrument are all in series communication with each other so that each body piece transmits sound as long as it is assembled in the instrument. It is this series communication of the body pieces 10, 12 and 14 which made it possible to give the instrument the neat appearance and practical shape which is particularly evident from Fig. 4. Thus, the bell piece 10 and part of the smaller diaphragm piece 12 form a convenient and easily accessible handle for the instrument when either of the two diaphragm pieces 12 or 14 is used. The bell piece 10 and the handle-forming part of the smaller diaphragm piece 12 are, moreover, sufficiently removed from the application surfaces of the diaphragm pieces 12 and 14 so as not to interfere in the least with the application of either diaphragm piece. The smaller diaphragm piece 12 still affords a very convenient grip even when the instrument is used in the manner shown in Fig. 7.

I claim:

1. A stethoscopic instrument having in combination ear tubes and a plurality of interconnected body pieces, said pieces including a bell piece connected at one end to the ear tubes and provided at its opposite end with a flared recessed portion, an intermediate piece having a shank projecting into the bell piece and a shoulder abutting said flared portion, said pieces having substantially horizontally disposed coaxial sound conduits therein, means for detachably connecting said shank to the bell piece, said intermediate piece having a normally extending portion provided at its outer end with a cavity, said extending portion having a substantially vertical sound passage communicating with the conduit in said intermediate piece, and an end piece having a tubular portion extending into said passage, means detachably connecting the tubular portion to the intermediate piece, said end piece having a recessed outer portion, a diaphragm closing said recessed portion, and means for connecting said diaphragm to the end piece, said pieces being normally connected together to provide a unitary assembly, and being constructed and arranged so

that when the end piece is removed, the adjacent piece constitutes the end piece for collecting and transmitting sounds to the ear tubes.

2. A stethoscopic instrument having in combination ear tubes and a plurality of interconnected body pieces, said pieces including a bell piece connected at one end to the ear tubes and provided at its opposite end with a flared recessed portion, an intermediate piece having a shank projecting 10 into the bell piece and a shoulder abutting said flared portion, said pieces having substantially horizontally disposed coaxial sound conduits therein, means for detachably connecting said shank to the bell piece, said intermediate piece 15 having a normally extending portion provided at its outer end with a cavity, said extending portion having a substantially vertical sound passage communicating with the conduit in said intermediate piece, an apertured diaphragm connected 20 to said depending portion, an end piece having a tubular portion extending through said apertured

diaphragm into said passage, means detachably connecting the tubular portion to the intermediate piece, said end piece having a recessed outer portion, a diaphragm closing said recessed portion, and means for connecting said last-mentioned diaphragm to the end piece, and a sleeve 5 valve rotatably mounted in the conduit in the intermediate piece, said sleeve valve having an opening adapted to be moved into and out of registration with said passage, said sleeve valve 10 also having a handle projecting beyond the end of said intermediate piece for actuating the valve to control the sound passing from the passage to the conduit, said pieces being normally connected together to provide a unitary assembly, and being 15 constructed and arranged so that when the end piece is removed, the adjacent piece constitutes the end piece for collecting and transmitting sounds to the ear tubes.

JAMES J. TYNAN. 20
